MASSAGE MACHINE

August Schumacher, Flushing, N. Y.

Application November 24, 1936, Serial No. 112,577

5 Claims. (Cl. 128—63)

The present invention relates to new and useful improvements in massage machines and has for its primary object to provide, in a manner as hereinafter set forth, a device of this character which is particularly adapted for treating the scalp.

Other objects of the invention are to provide a massage machine of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a massage machine constructed in accordance with the present invention.

Figure 2 is a detail view in bottom plan of the mat or belt.

Figure 3 is a top plan view of the machine.

Figure 4 is an end elevational view.

Figure 5 is a view in cross section, taken substantially on the line 5—5 of Fig. 1.

Figure 6 is a detail view in elevation of an intermediate portion of the reciprocating member.

Referring now to the drawings in detail, it will be seen that the embodiment of the invention which has been illustrated comprises an arcuate housing 1 of suitable material having an opening 2 in its upper portion at an intermediate point. As suggested in Figure 1 of the drawings, the arcuate housing 1 is adapted to be disposed above the head of the person using the device. The reference numeral 3 designates handles which are fixed on the housing 1 adjacent the ends thereof.

Slidably mounted in the housing 1 is a reciprocating member or bar 4 of suitable material. Of course, the reciprocating bar 4 is of a curvature conforming to that of the housing 1 and the arc of both the bar and the housing is a portion of a circle. The reciprocating bar 4 projects beyond the ends of the housing 1 and terminates in in-turned hooks 5. The reference numeral 6 designates a mat or belt of suitable flexible material having openings 7 in its end portions for the reception of the hooks 5 for connecting said belt to the reciprocating bar 4 for actuation thereby.

The belt 6 is provided with teats or the like 8 at an intermediate point for contact with the scalp.

At an intermediate point where the reciprocating bar 4 is exposed by the opening 2 in the housing 1, said reciprocating bar is provided with a notch 9. The reference numeral 10 designates a shaft which bridges the opening 2, said shaft being journaled in bearings 11 on the housing 1. Fixed on the shaft 10 is a cam 12 which is engaged in the notch 9 of the reciprocating bar 4. Mounted on a suitable base 13 on the housing 1 is an electric motor 14. The shaft 10 is driven from the electric motor 14 through reduction gears 15.

It is thought that the operation of the machine will be readily apparent from a consideration of the foregoing. The housing 1 is positioned above the head with the belt 6 engaged with the scalp, as shown in Fig. 1 of the drawings. Then, when the electric motor 14 is energized the cam 12 rapidly reciprocates the bar 4 in a manner to actuate the belt 6. The belt 6, of course, readily conforms to the shape of the head or any other portion of the anatomy being treated.

It is believed that the many advantages of a massage machine constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A massage machine comprising an arcuate housing, an arcuate bar mounted for reciprocation in said housing the arc of each of the housing and bar being a portion of a circle, a flexible belt connected to the end portions of said bar, and means for reciprocating the bar.

2. A massage machine comprising an arcuate housing, an arcuate bar mounted for reciprocation in said housing the arc of each of the housing and bar being a portion of a circle, a flexible massage belt connected, at its ends, to the end portions of said bar, a cam mounted on the housing and operatively engaged with the bar for actuating said bar, and means for actuating the cam.

3. A massage machine comprising an arcuate housing, handles on the end portions of said housing, an arcuate bar mounted for reciprocation in the housing, said bar projecting beyond the ends of the housing and terminating, at its ends, in hooks, a flexible massage belt connected, at its ends, to said hooks, and means on the

housing for reciprocating the bar, the arcs of said bar and housing being portions of a circle.

4. A massage machine comprising an arcuate housing, an arcuate bar mounted for reciprocation in said housing and projecting beyond the ends thereof, a flexible massage belt connected, at its ends, to the end portions of the bar, said bar having a notch therein at an intermediate point, the housing having an opening therein exposing the notch, a shaft journaled on the housing and extending across the opening, a cam fixed on said shaft and engaged in the notch for reciprocating the bar, and means for actuating the shaft, the arcs of said bar and housing being portions of a circle.

5. A massage machine of the class described

comprising an arcuate housing, handles on the end portions of said housing, an arcuate bar mounted for reciprocation in the housing and projecting beyond the ends thereof, a flexible massage belt, hooks on the ends of the bar for connecting the belt thereto, said bar having a transverse notch therein at an intermediate point, the housing having an opening therein exposing the notch, a shaft journaled on the housing and extending across the opening, a cam fixed on said shaft and engaged in the notch for actuating the bar, a motor mounted on the housing, and reduction gears operatively connecting the shaft to said motor for actuation thereby, the arcs of said bar and housing being portions of a circle. 15

AUGUST SCHUMACHER.
